UNITED STATES PATENT OFFICE.

ROBERT A. C. HOLZ, OF CLEVELAND, OHIO.

VACUUM APPARATUS FOR HYPEREMIC TREATMENTS.

1,000,001.

Specification of Letters Patent. Patented Aug. 8, 1911.

Application filed November 9, 1908. Serial No. 481,626.

To all whom it may concern:

Be it known that I, ROBERT A. C. HOLZ, a citizen of the United States, residing at Cleveland, in the county of Cuyahoga and

5 State of Ohio, have invented certain new and useful Improvements in Vacuum Apparatus for Hyperemic Treatments, of which the following is a specification.

This invention relates to improvements in 10 vacuum apparatus used particularly for hyperemic treatments.

One of the objects of the invention is to improve, in a general way, the efficiency and to extend the field of use of such devices, 15 and also to render their use more convenient by the provision of means whereby the air pump may be conveniently attached to or disconnected from the vacuum cup, and at the same time by doing away with the rubber tubes which heretofore have been used to connect the pumps and cups and by doing away with the expensive stop cocks used in connection with the tubes.

A still further object is the provision of 25 means whereby the degree of vacuum in the cup may be readily varied at any time before or after the pump is removed from the latter, so that in case it is desired to lessen the degree of exhaustion or vacuum or to 30 remove the cup from the body of the patient, it will be unnecessary to raise the cup from the patient's body to permit air to enter the cup.

The invention relates, therefore, particularly to the cup itself, to the means whereby it may be readily attached to the pump, and to the provision of certain valve features which will be brought out fully in the specification.

40 The invention may be briefly summarized as consisting in certain novel details of construction and combinations and arrangements of parts, which will be described in the specification and set forth in the appended claims.

For a better understanding of my invention reference is had to the accompanying drawing, in which—

Figure 1 is an elevation of the vacuum 50 apparatus constructed in accordance with my invention. Fig. 2 is a longitudinal sectional view of the same. Fig. 3 is a transverse section on a slightly enlarged scale, substantially along the line 3—3 of Fig. 2. Fig. 4 is a view showing a cup and socket

therefor, attached to the body of a patient and disconnected from the pump.

Referring now to the figures of the drawing, 10 represents the vacuum cup which is made preferably of glass, and which is provided with an open end 11, and at the opposite end with a neck 12 having a centrally located narrow passageway 13 through which air is admitted to or exhausted from the cup, and having an enlarged end portion 14. Secured to the neck 12 of the cup, is a shank or socket member 15 preferably cylindrical in shape and formed of metal and having at one end a recessed portion 16 which receives the neck 12 and is secured rigidly to the latter by means of cement 17 which is preferably waterproof, so that it will not be affected by hot water when the device is being sterilized. At the opposite end of the shank or socket member 15 is a second recess 18 which is threaded on the interior and is adapted to receive the threaded end of a pump to be referred to later. Between the two end recesses 16 and 18 the shank 15 is provided with a passageway 19 which is in alignment with the passageway 13 in the neck of the cup and forms a continuation thereof. The end of the passageway 19 adjacent the recess 18 is tapered, as shown in Fig. 2, and this tapered portion 80 forms a seat for the tapered head of a plug valve 20 which is preferably made of rubber and is provided with a shank which extends down into the passageway. This plug valve is held yieldingly down upon the seat 90 preferably by means of a spring 21 shown in Fig. 3. As will be explained later, by the provision of this plug valve, the pump can be removed from the shank or socket member 95 and the air will nevertheless be prevented from entering the cup.

In order that the degree of vacuum in the cup may be readily varied, I have provided in the shank or socket member intermediate its ends, a release valve 22. For this purpose I have provided at the periphery of the shank or socket member a lug or boss 23 having a centrally located passageway 24, the outer portion of which is threaded and receives the shank of an adjustable screw or valve member 25, and the inner end of which is preferably restricted with respect to the outer portion and communicates with the inner passageway 19 which extends longitudinally of the shank and communicates 110

with the cup. The boss is also provided with a small inlet port or passageway 26 which extends from the passageway 24 to the outer surface of the boss and through 5 which air may be supplied or admitted to the cup. The admission of air through this port is normally prevented by the adjustable screw or valve member 25, the inner end of the shank of which is tapered and is arranged 10 to enter the restricted portion of the passageway 24.

Any suitable form of pump may be employed with the cup, but as here shown, the pump consists of a cylindrical casing or cylinder 27 which is provided with a piston 28 pivotally connected to a link 29 which in turn is connected to a crank 30 mounted in the wall of the casing and having on the exterior of the casing a portion 31 adapted 15 to be grasped by the operator, so that when this portion is revolved the piston will be reciprocated longitudinally of the casing or cylinder. The piston 28 is provided with a port 32 which is normally closed by a flap 25 valve 33 secured to the surface of the piston and yieldingly held downward by a spring 34 so as to close the port. The end of the pump is provided with a threaded annular boss 35 which is adapted to be screwed 30 tightly into the threaded recess 18 of the socket member 15.

In the present case I have shown at the bottom of the pump a release valve 36 similar to the release valve 22 in the shank or 35 socket portion of the cup. This release valve 36 is formed by a lug 37 on the cup, said lug having a passageway 38 which communicates with the interior of the pump, and the outer end of which is threaded 40 and receives the shank of an adjustable screw or valve member 39, the inner end of which is tapered and is arranged to close the passageway so as to prevent the passage of air therethrough. As in the first instance, 45 the lug is provided with a port 40 which communicates with the passageway on the interior of the lug. Thus it will be seen that when the air has been wholly or partially exhausted from the cup, the pump 50 may be readily removed from the latter and on account of the valve, which is provided in the shank or socket member, the removal of the pump will not in any way change the degree of vacuum in the cup. A single 55 pump may, therefore, be employed with a large number of cups, any number of which may be attached to the body of the patient.

By doing away with the necessity for the rubber tubes which have heretofore been 60 used, the device can be kept in a much more sanitary condition, and can be more readily sterilized. Also the proper degree of vacuum can be more easily maintained in the cup than when rubber tubes and stop cocks are 65 employed.

The degree of vacuum in the cup can be very easily regulated, or the vacuum can be relieved entirely by the release valve 22 which I provide in the shank or socket member. Thus when this valve is provided, it 70 will not be necessary to raise the cup from the body of the patient or to insert the fingers under the end of the cup adjacent the skin of the patient to reduce the degree of vacuum or to remove the cup entirely. 75

The release valve such as I have shown need not be provided in the pump, if all the cups are of the construction here shown, but I prefer to provide such release valve in the pump, for the reason that the latter can then be used with cups which are provided with shank or socket members with or without the two valves here shown. Also the release valve in the pump will be of utility in some cases, such as when very small cups are employed which could not be conveniently equipped with the valves, or when the cup is intended to be applied to the body of the patient for a very short interval only. In the latter case there would be no necessity 80 for removing the pump from the cup. 90

I do not desire to be confined to the exact details shown, but aim in my claims to cover all modifications which do not involve a departure from the spirit and scope of my 95 invention.

What I claim as new and desire to secure by Letters Patent is:—

1. In a vacuum apparatus of the character described, a vacuum cup having a neck portion, a shank or socket member secured thereto, said shank having a valve which is normally closed but which is automatically opened when the air is being exhausted from said cup, and said shank having a manually operable release valve intermediate said first mentioned valve and the cup. 100

2. In a vacuum apparatus of the character described, a vacuum cup open at one end and having a neck portion, a shank or socket member having at one end a recessed portion which receives the neck portion and is rigidly secured thereto, an air pump adapted to be attached directly to the opposite end of said shank or socket member, said shank having a valve which is normally closed but is automatically opened by the pumping of the air from the cup, and said shank having a manually operable release valve intermediate said first named valve 110 and the cup. 115

3. In combination, in a vacuum apparatus, a vacuum cup having an open end and a neck portion at its opposite end, a shank or a socket member receiving said neck portion and rigidly secured thereto, said shank having an interior opening or passageway which communicate with the interior of the cup, a tapered valve seat at the outer end of said passageway, a valve 125 130

- plug normally engaging said seat and serving to retain the vacuum in the cup when the air is exhausted from the same, and said shank having a release valve, said release valve comprising a transverse passageway which communicates with the inner passageway or opening in the shank, an air inlet port communicating with said transverse passageway, and a screw valve member arranged to close said transverse passageway and to permit the passage of air to said cup when shifted from its normal position.
4. In combination, in a vacuum apparatus, a cup having an open end and a neck portion, a shank or socket member receiving said neck portion and rigidly secured thereto, said shank having a centrally located passageway which communicates with the interior of the cup, the outer end of said passageway forming a valve seat, a movable valve member normally engaging said seat, a manually operable release valve at the side of said shank, said release valve comprising a transverse passageway which communicates with said centrally located passageway intermediate said first mentioned valve and the cup, an air inlet port which communicates with said transverse passageway, a movable valve member in the form of a screw which when in its normal position prevents the passage of air through said port, an air pump, the ends of said shank or socket member and the pump having cooperating threaded portions whereby the pump may be rigidly secured to the socket member.
